Michael P. Arnone, Rivervale, N.J., assignor to Jacques Kreisler Manufacturing Corporation, North Bergen, N.J., a corporation of New Jersey

Filed Oct. 23, 1967, Ser. No. 9,126

Term of patent 14 years

(Cl. D48—27)

FIGURE 1 is a side elevation of a cigarette lighter showing one embodiment of my new design, the other side being a mirror image thereof.

FIGURE 2 is a front elevation of the cigarette lighter shown in FIGURE 1.

FIGURE 3 is a rear elevation of the cigarette lighter shown in FIGURE 1.

FIGURE 4 is a top plan view of the cigarette lighter shown in FIGURE 1.

The dominant features of my new design are shown by means of full lines in the drawings.

I claim:

The ornamental design for a cigarette lighter, substantially as shown and described.
